Patented Nov. 2, 1920.

UNITED STATES PATENT OFFICE.

ERLE READ, OF TALLULAH, LOUISIANA.

BACK-BAND.

1,357,823.

Specification of Letters Patent. Patented Nov. 2, 1920.

Application filed March 27, 1920. Serial No. 369,271.

To all whom it may concern:

Be it known that I, ERLE READ, a citizen of the United States, residing at Tallulah, in the parish of Madison and State of Louisiana, have invented certain new and useful Improvements in Back-Bands, of which the following is a specification, reference being had to the accompanying drawings.

10 This invention relates to an improved back band for use on various working animals, such as horses, mules and the like and a general and most important object of the invention is to provide a back band having 15 a broad portion engaging the back of the animal, so that the spread of the portion will discharge the weight of the pull more evenly over the back, thereby preventing injuring the back of the animal, which 20 would otherwise be the case in using an ordinary narrow back band now in use.

Another object is to construct the back band of two complementary portions or laminations with an intermediate padding of 25 any suitable material, preferably cotton, felt, hair or the like, and which may be any suitable or convenient shape or contour, preferably as shown, and having contracted 30 side parts to which the back band hooks or fasteners may be attached.

Still another object is the provision of a back band, the broad portions of the complementary parts of which are provided with darts, whereby the broad part of the back 35 band may conform to the curvature of the animal's back so that the weight of the pull may be more evenly distributed.

A further object embodies rolls of medium size upon the forward and rear edges 40 of the broad part of the back band in order to maintain the broad part in shape, preventing the same from turning up and also to withstand a portion of the pull when the back band is applied.

45 A still further object is the provision of perforations or openings throughout the greater part of the back band so as to prevent the back band from overheating the animal which would otherwise be the case 50 if it were not for the perforations.

An additional object involves an improved back band, the rolls upon the forward and rear edges of which being so arranged and constructed that they can be 55 formed by the edge portions of the opposite parts of the back band.

While the design and construction at present illustrated and set forth is deemed preferable, it is obvious that as a result of a reduction of the invention to a more practical form for commercial purposes, the invention may be susceptible to changes, and the right to these changes is claimed, provided they are comprehended within the scope of what is claimed.

60 The invention comprises further features and combination of parts, as will be herein-after set forth, shown in the drawings and claimed.

In the drawings:

70 Figure 1 is a view of the improved back band constructed in accordance with the invention, showing its application to the back of an animal shown in dotted lines.

Fig. 2 is an enlarged plan view of the 75 back band showing the same removed from the animal,

Fig. 3 is a sectional view on line 3—3 of Fig. 2,

Fig. 4 is a sectional view on line 4—4 of 80 Fig. 2,

Fig. 5 discloses detail views of one of the complementary parts of the back band.

Referring to the drawings, 1 designates the back band as a whole, which comprises 85 opposing complementary parts 2 and 3 of any suitable shape. These parts may be any suitable shape, preferably as shown, therefore they are provided with broad portions 5, which engage over the back of the 90 animal and partly upon the sides of the animal. The edges of these complementary parts are formed into a roll 6 and are stitched as shown at 7. These rolls act to withstand a part of the weight of the pull 95 or the strain which may be exerted upon the back band. In order that the back band may readily conform to the curvature of the animal's back, the opposite complementary parts are provided with darts 8. In 100 other words, the broad portions of the complementary parts are slit by cutting away a piece transversely through the centers, and the severed edges are designed to be stitched together. A filler of any suitable 105 material, preferably cotton, felt, hair or the like 15 is interposed between the two complementary parts, and then the parts are stitched at various locations as indicated at 10, so as to tuft and hold the filler in place. 110 At various locations, as indicated at 11, the back band is provided with a plurality of

perforations, which are stitched around their edges so as to prevent frayed edges.

The back band is provided with side extensions 12 and the opposing parts of these extensions form integral parts of the broad portions of the back band. The edges of the extensions are stitched as shown at 13, and are likewise padded or provided with a filler of hair, felt or the like 14. The extensions are connected to the usual form of back band hooks 16 as shown, to which the usual draft chains may be connected, as shown.

The invention having been set forth, what is claimed as new and useful is:—

1. In a back band for draft animals comprising a pad having a wide central portion so as to insure a widespread engagement

over the surface of the back of the animal, rolled edges on said central portion, side extensions on said central portion, and back band hooks on said side extensions. 20

2. A back band for draft animals comprising a pad having a relatively wide central portion to insure a wide-spread engagement over the surface of the back of the animal, said central portion having perforations and provided with rolled edges, said pad consisting of opposing complementary parts provided with an intermediate 25 30 filler, side extensions on the central portion, and back band hooks on said side extensions.

In testimony whereof I hereunto affix my signature.

ERLE READ.
